H. W. GOFF

AUTOMATIC TELEPHONE SWITCH

Filed April 8, 1922

Inventor:
Harold W. Goff

by W. E. Beattie, AMY

UNITED STATES PATENT OFFICE.

HAROLD W. GOFF, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed April 8, 1922. Serial No. 550,617.

To all whom it may concern:

Be it known that I, HAROLD W. GOFF, a citizen of the United States, residing at New York, in the county of New York, State of New York, have invented certain new and useful Improvements in Automatic Telephone Switches, of which the following is a full, clear, concise, and exact description.

10 This invention relates to automatic telephone exchange switching apparatus, and more particularly to the so-called coordinate switch.

15 The invention is peculiarly adaptable to a switching system of the type disclosed in Patent No. 1,515,735 issued to C. L. Goodrum et al. on November 18, 1924, but it will be apparent to those skilled in the art that this invention may be applied equally well 20 to perform the function of selector or connector switch.

25 The object of the invention is to provide an economical and improved form of coordinate switch which will be simple and reliable in operation, and readily accessible for repairs and replacements of operating parts.

30 A feature of this invention is the provision in a switch of the character above set forth, of individually removable rotatable grid elements on which the link conductors are insulatedly mounted. The grid elements being rotatable, are adapted to effect a wiping engagement with their associated 35 sets of flexed wire conductors.

Both sets of conductors are preferably in 40 the form of bare wires, one set, the link conductors, being helically arranged in the notches of insulating strips mounted on rotatable bars. The other set comprising 45 flexed wires extends through said notches and is normally held out of contact with the link conductors by means of a plurality of small cards of insulation one of which is 50 individual to each set of flexed conductors or contact members. Selecting and operating mechanism is provided whereby any card may be moved independently of the others to bring its associated conductors 55 into engagement with the adjacent set of link conductors.

Other features of invention will appear from the detailed description given below in connection with the accompanying draw-

ing, in which Fig. 1 is a partial front assembly view of the switch.

Fig. 2 is a partial side assembly view showing one set of contact members in operated position.

Fig. 3 is a perspective partial view of an assembly of a rotatable link bar, notched insulating strip and a set of conductors helically arranged thereon.

The sets of link conductors 1, 1¹, 1², and 1³ are preferably helically arranged in the notches of insulating strips 2 which are mounted in channel shaped members 3 and held secure thereon by any suitable means. The members 3 are mounted on bars 4 rotatably mounted on the switch frame (not shown) and held secure thereon by means of bolts, screws or rivets 5. Magnets 23 having armatures 24 are provided for operating the bars 4.

Upright supports 6 of insulating material 75 also attached to the switch frame (not shown) are disposed at right angles to conductors 1, 1¹, 1², and 1³, and carry the flexible wire contact springs or conductors 7, 8, 9, 10 and 7¹, 8¹, 9¹, 10¹, etc. The supports 6 may carry any desired number of sets of contact springs dependent upon the switch capacity desired. For simplicity of illustration, however, only two such sets are shown on support 6 in the partial view of Fig. 2, the supports being omitted in Fig. 1. The free ends of each set of conductors 7, 8, 9, 10, etc. extend through an aperture 11 of a plate member or card 12 of insulating material, into the notches of insulating strip 2. The card 12 is mounted on a resilient support 13 which is fixed at one end portion to the upright support 6, and has its free end 14 normally resting in the bottom of a V-shaped groove 15 of the downwardly extending lug 16 which is preferably made integral with the channel-shaped member 3. The support 13 is flexed to normally hold the card 12 and the corresponding contact springs flexed up out of contact with the link conductors.

Individually associated with each support 6 is a bar 17 which is journaled at its end portions in the switch frame (not shown). Securely attached to each bar 17 is an armature 18 which is arranged to be attracted by electromagnet 19 whereby the bar 17 is operated through a small angular displace-

ment. The bar 17 is provided with a flexible arm 21 adjacent each set of contact wires carried by the support 6.

Each horizontal bar or link bar, as it may be properly termed, is provided with a number of rigid arms 20. Each of these arms 20 is individually associated with a set of active contact wires and an arm 21, and has a vertically disposed portion 25 engaging in a vertical slot 26 of the card 12, and serving as a guide for the lower portion of the card.

The cards 12 are each provided at their lower ends with a horizontal slot 22 in which the free end of an associated arm 21 is adapted to move into engageable relation with arm 20 of bar 4, the arm 21 being normally out of the path of said arm 20.

When the vertical bar 17 is rotated out of its normal position by electromagnet 19 the end portion of arm 21 is driven into engageable relation with arm 20 and the subsequent rotation of bar 4 through the energization of magnet 23 results in lowering the operating card 12 so as to permit the contact wires 7, 8, 9, 10 to engage the link conductors 1, 1¹, 1², and 1³, respectively with a wiping movement. The operated link bars together with arms 20 thereon remain in their off normal position throughout the duration of the connection, but the vertical bars 17 may be immediately restored to normal.

Following the engagement of the contact wires and link conductors, the card 12 continues its downward movement and frees the wires 7, 8, 9, 10 from contact with the card, so that subsequent movement of the bar 17 in the establishment of other coexisting connections, will not be transmitted through the card 12 to the wires to disturb their contact with the wires 1, 1¹, 1², 1³.

What is claimed is:

1. In a switching mechanism, a plurality of notched insulating members, sets of conductors helically arranged thereon, sets of flexible contacts arranged in rows coordinate to said sets of conductors, and means for selectively establishing connection between said sets of conductors and said sets of contacts.

2. In a switching mechanism, a plurality of sets of rotatable members, sets of conductors helically arranged on said members, a plurality of sets of flexible contact members arranged in rows coordinate to the first-mentioned sets, a selecting bar for each row of contact members, a plurality of arms on each of said selecting bars, said arms associated individually with said sets of contact members but normally out of operable relation therewith, and means operable through the conjoint operation of said rotatable members and said selecting bars to effect engagement between said sets of contact members and said sets of conductors.

3. In a switching mechanism, a plurality of notched insulating members, conductors helically arranged in the notches thereof, a plurality of sets of flexible conductors arranged at right angles to said first-mentioned conductors and extending through the notches of said insulating members but normally out of contact with said conductors, a selecting bar individual to each row of flexible conductor sets, a rotatable operating bar for each of said insulating members, means for actuating said bars individually, and means whereby the conjoint actuation of one of said selecting bars and one of said operating bars establishes a connection between a set of helically arranged conductors and a set of flexible conductors at their intersecting point.

4. In a switching mechanism, sets of notched rotatable members, conductors seated in said notches, a plurality of sets of flexible conductors extending through said notches, a movable support for each set of flexible conductors normally maintaining said conductors out of contact with the helically arranged conductors, a selecting bar individual to each row of flexible conductors, an operating bar for each of said rotatable members, means for actuating said bars individually, and means whereby the conjoint actuation of one of said selecting bars and one of said operating bars establishes a connection between a set of flexible conductors and a set of helically arranged conductors at their intersecting point.

5. In a switching mechanism, a plurality of sets of flexible conductors, a plurality of notched members, conductors seated in said notches and helically wound on said members, means for individually operating said members, a plurality of bars associated with said rows of flexible conductors, and means for individually operating the said bars, the conjoint operation of one of said members and one of said bars being effective to move a set of said flexible conductors and to impart a rubbing action between said flexible conductors and their associated helically arranged conductors at their intersecting point.

6. In a switching mechanism, a multiple contact bank comprising a plurality of sets of bare wire conductors, and a notched insulating support therefor, the wires of one of said sets being guided into engagement with the other set by said notches.

7. In a switching mechanism, movable members, sets of conducting elements helically arranged thereon, sets of flexible contacts arranged in rows coordinate to said sets of conducting elements, and means for selectively establishing connections between said sets of elements and said sets of contacts through the movement of said mem-

bers, the movement of said members effecting a wiping contact between engaged elements and contacts.

8. In a switching mechanism, movable members, sets of conducting elements helically arranged thereon, sets of flexible contacts arranged in rows coordinate to said sets of conducting elements, means for selectively establishing connections between said sets of elements and said sets of contacts through the movement of said members, and means effective upon continued movement of said members to produce a wiping contact between engaged elements and contacts.
9. In a switching mechanism, a plurality of sets of conductors arranged in parallel rows, a plurality of sets of flexible contacts arranged in rows coordinate to said rows of conductors, each of said contact sets being adjacent to one of said sets of conductors, an operating card for each of said sets of contacts, a bar associated with each of said first-mentioned rows, a plurality of arms on said bar each associated with one of said

cards and serving as a guide therefor, a 25 selecting bar individual to each row of contact sets, and an arm on each of said selecting bars associated with each of said first-mentioned arms, the conjoint operation of one of the first-mentioned arms and one of 30 the second-mentioned arms being effective to actuate an operating card to effect engagement between a set of conductors and a set of contacts.

10. In a switching mechanism, supporting 35 members, a notched guide member secured to each of said supporting members, sets of conducting elements arranged thereon, a plurality of sets of flexible conductors extending through the notches of said guide members but normally out of contact with said conducting elements, and means for establishing connections between said sets of elements and said sets of conductors.

In witness whereof, I hereunto subscribe 45 my name this 5th day of April A. D. 1922.

HAROLD W. GOFF.
